C. WHITE,
INTERNAL COMBUSTION ENGINE,
APPLICATION FILED OCT. 16, 1919.

1,351,980.

Patented Sept. 7, 1920.

Charles White Inventor
By his Attorney
Phillips Abbott.

UNITED STATES PATENT OFFICE.

CHARLES WHITE, OF GLEN COVE, NEW YORK.

INTERNAL-COMBUSTION ENGINE.

1,351,980.

Specification of Letters Patent. Patented Sept. 7, 1920.

Application filed October 16, 1919. Serial No. 830,964.

To all whom it may concern:

Be it known that I, CHARLES WHITE, a citizen of the United States, and a resident of the town of Glen Cove, county of Nassau, 5 and State of New York, have invented a new and useful Improvement in Internal-Combustion Engines, of which the following is a specification, reference being had to the accompanying drawing.

10 As is well known, the accumulation of carbon, and gummed oil about the intake and exhaust valves and the valve stems of internal combustion engines is a source of much trouble and expense in the running of 15 automobiles. It is the purpose, therefore, of this invention to provide inexpensive and easily operated means whereby the carbon and gummed oil may be efficiently and inexpensively removed from the parts referred 20 to and their lubrication easily and quickly effected.

The figure of the drawing is a vertical sectional view of a portion of an automobile cylinder, showing an intake valve and one 25 form of my invention applied thereto.

In the drawing, 1 represents a part of the inner wall of a cylinder, 2, 2, the water jacket passages, 3 one of the intake valves, 4 the stem therefor, 5 the usual spring, 6 30 the rod which extending downwardly engages with the cams or eccentrics, 7 a nipple which is threaded into the outer wall of a part of the water jacket, as shown, and is tightly entered into an opening 8 made 35 in the bored stem guide part of the casting. 9 is a coupling nut whereby the ferrule 10 of a pipe 11, which may be rigid, as of metal, or flexible, as of rubber, or other suitable material, as preferred, may be tightly 40 clamped to the exposed end of the nipple. 7. 12 is a small reservoir with which the opposite end 13 of the pipe engages. 14 is a waste plug to draw off the contents of the reservoir 12. 15 is the filling opening for 45 the reservoir. 16 is a cap adapted to seal the opening 15. 17 is a pipe which enters the upper end of the reservoir and 18 is an air pump of any suitable construction.

The operation is as follows: 50 Kerosene, or equivalent carbon and gummed oil cutting and removing liquid is first put into the reservoir and the cap 16 placed in position. Should carbon or gummed oil accumulate upon the valve, its 55 seat or stem, then a few strokes of the air pump 18 will generate air pressure upon

the top of the kerosene, which will be forced from the reservoir through the pipe 11 and nipple 7 against the side of the valve stem 4, and owing to the permeative character of 60 kerosene, or its equivalent, it will be distributed throughout the length of the valve stem, and a portion carried upwardly and spread laterally over the under side of the valve 3, so as to cut and remove the objectionable deposits upon the valve and its seat. 65 The amount of kerosene thus injected will depend upon the desires of the chauffeur or operator, which obviously will depend upon the foulness and size of the parts. The 70 carbon and gummed oil thus disintegrated and washed or shoved aside will partly move downwardly along the stem and drop through the spring 5, to an unobjectionable place, from which it may be periodically removed, and that which comes from the valve and its seat will drop into the water jacket or manifold as the case may be, from which it also will be periodically removed.

It will be understood that although I illustrate the invention as applied to a single cylinder, that there may be as many pipes 80 11 as there are cylinders, or that a single pipe 11 may connect the reservoir with a suitable crosshead or manifold pipe, from 85 which individual connections with the several cylinders may be made. It will of course be unnecessary to illustrate these details because they are elementary in such mechanism. Moreover they will vary when 90 used in conjunction with engines of differing constructions. Also it will be noted that the nipples 7 may be so located as to discharge upon any preferred part of the valve stem, or the valve, or its seat, and that 95 there may be more than one nipple discharging upon the same. It will also be noted that the reservoir and pump may be located at any convenient place upon the car, and if desired, the pump plunger may be manipulated from the chauffeur's seat. I prefer to arrange the nipple 7 at an upward angle as illustrated, so that the tendency of the pressure applied to the kerosene may be to impel it upwardly, so that 100 it may more surely distribute itself upon all parts of the stem and valve. Gravity will tend to spread it in the opposite direction.

The apparatus described and illustrated shows one form only in which my invention 110 may be embodied and many departures therefrom may be made and still the essen-

tials of the invention be retained. I therefore do not limit myself to such details.

I claim:

1. In combination with an internal combustion engine provided with a valve which communicates with the interior of the cylinder, devices for removing carbon and the like from the valve and its stem comprising a reservoir for kerosene or similar carbon-removing material, having a sealing device, an air pump discharging into the upper part of the reservoir and a pipe extending from the lower part of the reservoir and discharging against the stem of the valve.
2. In combination with an internal combustion engine provided with a valve which communicates with the interior of the cylinder, devices for removing carbon and the like from the valve and its stem comprising a reservoir for kerosene or similar carbon-removing material, having a sealing device at its upper part and a draw-off plug at its bottom, an air pump discharging into the upper part of the reservoir and a pipe extending from the lower part of the reservoir to and through the cylinder structure and discharging upon the stem of the valve.
3. In combination with an internal combustion engine provided with a valve which

communicates with the interior of the cylinder, devices for removing carbon and the like from the valve and its stem, comprising a reservoir for kerosene or similar carbon-removing material, having a filling device at its upper part and means to close the filling device air-tight, an air pump adapted to pump air into the upper part of the reservoir and a pipe extending from its lower part to and through the cylinder structure and discharging upon the stem of the valve.

4. In combination with an internal combustion engine having a cylinder and a stemmed valve connecting therewith, a reservoir provided with means whereby it may be filled with kerosene or other carbon-removing material and means to close the filling opening air-tight, means to generate air pressure upon the top of the contents of the reservoir and a pipe extending from the lower part of the reservoir to the cylinder structure, the cylinder structure being provided with an opening in continuation of the said pipe extending at an upward angle and discharging upon the stem of the valve.

In testimony whereof I have signed my name to this specification.

CHARLES WHITE.
